Neil H. Pleton,
his ATTORNEY

UNITED STATES PATENT OFFICE

OSCAR S. FIELD, OF ROCHESTER, NEW YORK, ASSIGNOR TO GENERAL RAILWAY SIGNAL COMPANY, OF ROCHESTER, NEW YORK

LIGHT SIGNAL

Application filed June 14, 1929. Serial No. 370,861.

This invention relates to railroad light signals and more particularly pertains to an adjustable spring suspension mounting for light signals of the movable color screen type.

5 In practice, light signals are mounted upon railroad ties, cement foundations along the wayside, signal bridges and even railroad bridges. These various foundations are in such close proximity to the track, that the 10 passage of heavy trains produces vibrations, which are transmitted to the signals in varying degrees according to the particular case involved. In view of these conditions, the 15 present invention provides means whereby the severity of the vibrations may be somewhat reduced in particular cases where it is desirable. This objective is obtained by provision of a spring mounting, which is peculiarly adaptable to light signals, in as much as it 20 furnishes an adjustable means for varying the angle which the light beam assumes in respect to the plane of the track rails.

With such an arrangement applied to a 25 light signal having a movable color screen, such for instance as set forth in my pending application Ser. No. 128,437, filed August 10, 1926, additional protection is provided for the pivot points of the movable vane, which if they should become worn and distorted 30 might cause the movable vane to stick in a clear position producing a false indication. Such a condition is obviously very undesirable and the possibility of such an occurrence may be greatly reduced by the application 35 of the present invention.

In view of the above considerations and others, it is proposed to provide according to 40 the present invention, a means for mounting light signals whereby the severity of the vibrations due to passing trains may be considerably reduced, by the provision of a spring suspension mounting. It is a further object of the invention, to provide a spring mounting which is adjustable, so that the light beam of the signal may be directed at various ranges along the track way.

Other objects, purposes and characteristic 45 features of the present invention will be in 50 part obvious from the accompanying draw-

ings and in part pointed out as the description of the invention progresses.

Fig. 1 is a side elevation of a signal supported by the spring suspension mounting as included within the invention; 55

Fig. 2 is a front elevation of Fig. 1;

Fig. 3 is a section, on the lines 3—3 of Fig. 2.

Referring now to the drawings, Fig. 1 shows diagrammatically a signal of the movable color screen type, having a sector 1 mounted upon a pinion shaft 2, which rotates upon suitable supports under the controlling effect of a motor means 3, in such a manner that color screens mounted upon the sector 1 pass through the focal point of a light source 4 in conjunction with a reflector 5. Such a light signal of similar arrangement, having a movable color screen, is fully described in my above referred to application Ser. No. 128,437. 60 65 70

In this specific illustration, the sector 1, pinion shaft 2, motor means 3, light source 4 and reflector 5 are mounted within a suitable case 6, which case 6 is pivotally mounted at two points and adjustably mounted at a third point. The pivot points are provided by two plunger bolts 7, to which the case 6 is attached by bearing pins 8 suitably secured by cotter pins or other means. These 80 plunger bolts 7 pass through coil springs 9, holes 10^a within the base casting 10 and are then secured by nuts 11. 75 85

It can be seen from Figs. 2 and 3, that the plunger bolts are provided with rectangular heads, which are horizontally supported by the projections 10^a and 10^b of the base casting 10. Also, the plunger bolts 7 are vertically supported by springs 9, in such a manner, that said bolts 7 are resiliently urged or biased in an upward direction which is limited by the nuts 11. This arrangement allows the plunger bolts 7 to slidably move in respect to the base casting 10 within holes 10^a and the slots provided by projections 10^a and 10^b. It is also noted by reference to Fig. 2, that horizontal movement is further limited by projections 6^a and 6^b of the casing 6, which come into contact with the projections 10^a and 10^b. 90 95 100

The base casting 10 is of what might be termed webbed construction, as contrasted with solid construction, and has a base plate 10°, two leg portions for supporting the two pivoted points of suspension, which leg portions are interconnected by a web forming a support for the adjustable point of suspension. It is of course understood, that the base plate 10° may assume many different forms for mounting signals according to standard practices on signal masts and bridges, but for convenience in showing, this specific illustration has been provided for mounting on the level surface of a tie T, being secured by suitable lag screws 17.

The adjustable point of suspension is provided by the projections 10°, which form a forked shaped member for receiving the adjusting means, which adjusting means is provided with connection to the case 6 by the stud bolt 12. A plunger bushing 13 is formed with an upper flanged portion providing a stop for the coil spring 14, and also furnishing by its flattened faces, a means for turning said bushing 13 with a wrench. The bushing 13 is threaded on the stud bolt 12 and locked into place by the nut 16 after the spring 14 and grooved washer 15 have been put into place, so that the plunger bushing 13 is biased to an upward position with the nut 16 acting as a stop against the projections 10°.

It is now easily seen, when it is desired to tilt the signal case 6 upon the pivot points provided by the bearing pins 8 in the plunger bolts 7, that it is merely necessary to slightly loosen the lock nut 16 and turn the plunger bushing 13 on the bolt 12, until the desired position is obtained and then turn the lock nut 16 tightly against the plunger bushing 13.

It is noted that the projections 10° are formed on an arc, so that when the angular position of the light signal case 6 is altered in respect to the base member 10, the spring 14 and its washer 15 are held in a cup shaped support without being unevenly tensioned. Also, the nut 16 is thereby provided a curved support by the projections 10°, so that said nut 16 assumes a similar position in respect to projections 10° for each adjustment made to said light signal case 6. The radii of the arc formed by projections 10° coincide with certain of the tangents of a circle having the pivot points of said plunger members 7 as a center, with the radius of said circle perpendicular to said plunger bushing 13 and of a valve equal to the distance between said center of said circle and the center of said plunger bushing 13.

Thus, a means for mounting a light signal upon a spring cushioned base has been provided, which is readily adjustable and is peculiarly adaptable to light signals of the movable color screen type.

It is to be understood that this specific

embodiment of the present invention is given solely by the way of illustration, and that various modifications and alterations may be made without departing from the spirit of the invention as set forth by the appended claims.

What I claim is:—

1. A resilient and adjustable supporting structure for light signals for railroads, comprising, in combination with a light signal case and a fixed base, of two spaced plungers pivotally connected to said case and slidably supported and guided by said base for up and down movement, a third plunger fixed to said case and adjustably supported and guided by said base for up and down movement for various angles in a vertical plane, a spring on each plunger engaging the base and urging said plunger upwardly, and adjustable means on each plunger positively limiting its upward movement relative to its said base, whereby said light signal case is resiliently supported in the different positions in which it may be tilted by positioning said adjusting means.

2. A structure for adjustably supporting light signals for railroads comprising in combination, a light signal case, a base member, two plunger members, a coil spring sleeved on each of said plunger members, means pivotally attaching said plunger members to said light signal case, means slidably mounting said plunger members on said base member, a plunger bushing adjustably attached to said light signal case, a coil spring sleeved on said plunger bushing, means slidably and swingably attaching said plunger bushing to said base member, whereby said light signal case is movably attached to said base member and is biased by said springs to one extreme position in respect to said base member and whereby said extreme biased position is adjustable.

3. A structure for adjustably supporting light signals for railroads comprising in combination, a light signal case, a base member, a plurality of coil spring members, a plurality of plunger members pivotally attached to said light signal case and slidably mounted on said base member with one of said coil spring members sleeved on each of said plunger members, a plunger bushing adjustably attached to said light signal case, an adjustable means slidably and swingably mounting said plunger bushing to said base member with one of said coil springs sleeved on said plunger bushing, said coil springs resiliently supporting said light signal case, whereby said light signal case is resiliently supported in different adjusted positions in respect to said base member.

4. A structure for adjustably supporting light signals for railroads comprising in combination, a light signal case, a base member, a plurality of coil spring members, a plurality

of plunger members pivotally attached to said light signal case and slidably mounted on said base member with one of said coil spring members sleeved on each of said plunger members, a plunger bushing adjustably attached to said light signal case, an adjustable means slidably and swingably mounting said plunger bushing to said base member with one of said coil springs sleeved on said plunger bushing, said coil springs resiliently supporting said light signal case, and means including a forked support assuming an arc having radii which coincide with certain of the tangents of a circle having the pivot points of said plunger members as a center with the radius of said circle perpendicular to said plunger bushing and of a value equal to the distance between said center of said circle and the center of said plunger bushing, whereby said light signal case is resiliently supported in different adjusted positions in respect to said base member.

5. A structure for adjustably supporting light signals for railroads, comprising a light signal case, two plunger members pivotally connected to said light signal case, a plurality of coil spring members, a base member fixedly supporting said plunger member and said light signal case against movement horizontally and movably supporting said light signal case in a vertical direction by the interposition of said coil springs sleeved on said plunger members, said plunger members passing through said base member, lock nuts 30 limiting the upward movement of said plunger members, a stud bolt connected to said light signal case, a plunger bushing threaded on said stud bolt, one of said coil springs passed over said bushing, a grooved washer interposed between said coil spring and a supporting portion of said base member, a lock nut threaded on said stud bolt to lock the position of said plunger bushing and to limit the movement of said stud bolt in respect to said base member, whereby said light signal case is adjustably spring cushioned in respect to said base member.

In testimony whereof I affix my signature.
OSCAR S. FIELD.
